UNITED STATES PATENT OFFICE

HARRY L. MYERS, OF TOLEDO, OHIO, ASSIGNOR TO THE AMERICAN FLOOR SURFACING MACHINE COMPANY, OF TOLEDO, OHIO, A CORPORATION OF OHIO

SANDING MACHINE

Application filed July 17, 1930. Serial No. 468,624.

This invention has reference to certain structural improvements and refinements embodied in the development of a machine for abrading and sanding work susceptible of diversified usage in working, dressing, and finishing plane surfaces.

Visualized more specifically, the inventive conception comprehends a portable belt sanding machine such as may be unitarily referred to as a sanderplane, such as may be converted for sanding edges and butt ends of floors on the one hand, or adjusted for cabinet, trim, bench and repair shop sanding on the other hand.

One feature of novelty is predicated upon a manually steered and manipulated sanderplane propelled through the medium of an electric prime mover characterized by a frame structure having a multiplicity of individual selectively usable handles to afford convenient means for fulfilling the requirements of a combination machine of this class.

In developing this machine, I have evolved and produced a unique co-ordination of mechanical details such as permits the machine to be used to advantage for innumerable purposes in conditioning flat wood surfaces whether new, marred, painted or otherwise, thus enabling the machine to deliver the utmost in quantity and quality of work resulting in smooth finish with a negligible amount of effort and minimum operating costs.

Analyzed structurally and more specifically, I have developed a light-weight belt sander with exceptional speed and assured dependability individualized by a special frame construction to accommodate interchangeable belt guiding units at the front of the same, whereby to permit standardization and interchanging of these units so as to permit the same general construction to be efficiently employed for floor edging across the butt end, along the edges, or stair landings, to expedite and facilitate sanding of boats, table-tops, furniture, refinishing of school desks and other analogous tasks.

Many other structural features and ac-

companying advantages will become clearly evident from the following detailed description and the companion drawings affording a pictorial illustration of the complete machine and co-related parts.

55

In the drawings:

Figure 1 is a side elevational view of the complete portable sanderplane constructed in accordance with the present inventive conception and illustrating the specific organization used for floor edge sanding purposes.

60

Figure 2 is a view exactly like Figure 1 showing the edging shoe unit removed and replaced by a special guide equipped unit adapting the structure for bench and mill work.

65

Figure 3 is a plan view of the structure shown in Figure 2.

Figure 4 is a rear end elevation of the duplex carriage structure constituting an important factor of the invention.

70

Figure 5 is a view like Figure 4 with the wheel-equipped yoke removed to expose the adjustable roller mounting.

75

Figure 6 is an enlarged vertical section taken approximately on the plane of the line 6-6 of Figure 3.

Figure 7 is an enlarged fragmentary sectional and elevational view on the line 7-7 80 of Figure 2.

Figure 8 is a detail vertical section on the line 8-8 of Figure 4.

Figure 9 is a horizontal section on the line 9-9 of Figure 1.

85

Figure 10 is a top plan view of a belt backing platen.

Figure 11 is a plan view of the resilient edging shoe.

Figure 12 is a top plan view of the interchangeable unit employed for bench work.

90

Figure 13 is a view of the unit shown in Figure 12 observing the same in a direction from left to right.

95

Figure 14 is a longitudinal sectional view on the line 14-14 of Figure 12.

Figure 15 is a side or edge elevation of the same observing the structure in a direction from left to right in Figure 13.

100

Figure 16 is a fragmentary detail section on the line 16-16 of Figure 14.

Figure 17 is a plan view of the companion interchangeable unit embodying the edging shoe.

Figure 18 is a section on the line 18-18 of Figure 17.

Figure 19 is a diagrammatical illustration showing the utilization of the wheeled truck (the truck being illustrated rigid).

Figure 20 is a view like Figure 19, showing the adjustable truck to emphasize the importance of this detail.

Referring now to the drawings by reference numerals, it will be observed that 21 designates a support of a portable nature hereinafter generally recited as a frame. This is characterized by a substantially flat plate 22 having a downturned end 23 constituting a curved apron or shield partly embracing a rubber-covered pulley 24. Incidentally, the "pulley" is broadly referred to at points in the description as an anti-friction drive for an associated endless abrasive belt 25.

The plate is fashioned along one longitudinal edge to accommodate the source of power here shown in the form of a vertical electric motor 26. On the frontal portion 30 of the plate is a steering handgrip 27. Extending somewhat in a plane with the top of the plate at the curved apron end is an outstanding flange 28 equipped with stop screws 29 and lock nuts 30 which serve a purpose to be hereinafter described.

It is appropriate to mention here that the numeral 31 designates a depending handle located centrally of the motor and co-operable with the handle 27 for using the device as a bench plane. On this same side and above the handle is a boxing 32 containing a switch 32' and fashioned to accommodate a wall plug cord (not shown) for supplying current to the motor. The numeral 33 designates a supplemental handle having a bracket 34 detachably mounted on the boxing 32. This permits the handle to be removed in places inconvenient of access.

The handle 33 is used in conjunction with the handle 27 when employing the machine for floor edging purposes.

Examining Figures 6 and 9, it will be noted that the frame includes a hollow cast gear housing 35 depending from the rear end portion of the plate and serving to accommodate the motor shaft 36, and the worm 37 and its companion worm 38. The gear is carried by a horizontal driven shaft 39 journaled in appropriate bearings as represented in Figure 9. The projecting end portions of this shaft 39 carries the aforesaid rubber-covered pulley 24.

Incidentally, this power transmission means is commercially important but not claimed in this particular application.

Formed integral with the depending portion of the casting, as shown in Figure 7, is a central transverse suspension flange 40. Suitably fastened to this is a separable bracket including an attaching plate 41, an outstanding cylindrical keeper stud 42 and a tubular mounting stem 43. The stem is formed at longitudinally spaced points with keeper sockets 44 and 45 respectively.

This arrangement forms a standardized attaching device or mounting for the interchangeable units such as are used alternately for floorwork on the one hand, and benchwork on the other. In each instance, there is a spring 46 provided which is confined in the bore of the tubular stem 43 as shown in Figure 7.

For the sake of distinction, the unit detailed in Figures 12 to 16 will be known as the bench unit. The one represented in Figure 17 will be known as the edger unit. The bench unit detailed in Figures 12 to 16 comprises a cast socket 47 which is slipped over the stem 43. As seen in Figure 7, there is an end plate 48 receiving the thrust of one end of the coil spring 46. The numeral 49 designates a web carrying a lined eye or collar 50 which slips over the stub 42. The numeral 51 indicates a spring-pressed latch of appropriate construction for selective reception in the keeper holes or sockets 44 and 45 respectively.

Under normal circumstances, however, the latch is disengaged and the spring 46 is constantly under tension. The side extension 52 is formed with a screwthreaded socket to accommodate the adjusting bolt 53 which is engageable with an arm 54 pivotally mounted as at 55 between the furcations of the bifurcated bracket 56. It will be noticed that a coiled expansion spring 57 is interposed between the free ends of the arm 54 and the extension 52 to exert pressure against the arm to bring about automatic adjustment of the guide member 58.

This member 58 is formed of sheet metal and is somewhat V-shaped in cross-sectional configuration, having curved terminal ends 59, a flattened crown portion 60, and depressed intermediate portions 61 in its rearwardly diverging walls. This is to provide a simple guide for the aforesaid endless abrasive belt and at the same time dissipate heat.

So as not to detract from the efficient dissipation of heat, I provide the guide with a central block 62 fastened on a rigid stub shaft 63 detachably bolted to the arm 54. This arm and bolt and pivotal mounting construction is to permit lateral adjustment of the guide 58 to aid in properly alining the belt.

The numeral 64 designates a belt guide. The bench unit is shown in complete operative position in Figure 2, at which time the

belt 25 is trained over the guide 58 as well as the pulley 24. At this time, as before indicated, the spring 46 is under tension, and maintains the complete unit expanded 5 to exert yieldable pressure against the adjacent end run of the belt.

I call attention at this time to the numeral 65, which designates a backing plate to be hereinafter known as a yieldable platen. As 10 detailed in Figure 10, this comprises a flat resilient metal plate having slits 66 formed therein, having the toe 67 upturned and the heel 68 upturned at an angle to permit it to be anchored on the casting of the frame as 15 represented in Figures 1 and 2. This presses yieldably against the inner surface of the lower flight of the belt and in the belt arrangement in Figure 2, it maintains the forward portion of the lower flight of the belt 20 in tangential relationship to the lower portion of the guide element 58.

The floor edger unit is substantially the same in construction in its major details. For example, as shown in Figure 17, it comprises a cast socket 69, a guide eye 70, a 25 spring-pressed latch 71. The numeral 72 merely designates a bumper or roller. The belt guide is indicated at 73 and the extension at 74, this carrying the adjusting screw 30 75 for the associated arm 76. The arm 76 is pivotally mounted at 77 on the extension bracket 78. This arrangement is for adjusting the miniature guide pulley or idler roller 79.

Attached to the casting below the pulley 79 is the resilient edging shoe 80. This embodies a plurality of independent bendable or flexible fingers 81 having short vertical terminals 82 allowing the frontal flight of 40 the belt to recede at the approximate angle illustrated at Figure 1 when the device is used for edging purposes.

The numeral 83 represents an extensible arm carrying a channel 84 having a rubber bumper strip 85 arranged therein to form a resilient buffer to regulate the distance of approach within the vicinity of the mop board.

Attention is now invited to the duplex 50 carriage construction constituting an important factor of the rear end portion of the structure. This is located on the rear of the frame rearwardly of the propulsion pulley 24. It embodies two main parts, 55 namely a wheel-equipped truck independently adjustable with respect to a roller-pin constituting a work engaging runner. The wheel truck comprises a suitably designed yoke 86 having its end portions constructed to accommodate the floor contacting wheel 87.

The arms 88 on the ends of the yoke are rockably mounted on the journal pin extensions 89 of the work engaging runner or 60 roller 90. This allows the truck yoke to be

raised or lowered to render the wheels effective when using the machine for floor edging purposes or to move the wheels to an out-of-the-way position above the elevating plane of the roller 90 to permit the latter to 70 come into play for bench work.

Thus I have a wheel-equipped, adjustable truck susceptible of independent use with respect to the runner roller 90. The roller 90 is turnable on the axle 89 which is mounted fixedly in bearings 91 (see Figure 5) carried by the carrier 92. The carrier includes a top flange 93 and a bottom flange 94.

There is a screw 95 on the flange 94 and an adjustable stop screw 96 on the top flange 93. As shown in Figure 8, these screws are engageable with the inwardly extending flanged portion 97 of the truck. Incidentally the numeral 98 designates a spring surrounding the screw 95 and exerting an upward thrust on the truck, so that upon releasing the retaining screw 96, the spring will come into play to lift the truck automatically to an out-of-the-way ineffective position. Thus, the spring lifts and holds 90 the truck up.

The entire carrier 92 and the truck mounted thereon is adjustable as a unit as shown by the construction represented in Figure 5. This includes slotted webs 97 and cap bolts 97' threaded into the apron. In Figure 8, it will be observed that the aforesaid bolts 29 constitute set screws for adjusting the tilt or position of the carrier. It is to be mentioned in this connection that this arrangement permits the truck wheels to be regulated for effective floor surfacing operation. This is an essential characteristic of the machine which will be evident by comparing Figure 19 to Figure 20.

As a matter of diagrammatic illustration here, the floor is represented by the numeral 99 while the numeral 100 indicates the supposedly rigid truck having floor engaging wheels 101. The numeral 102 designates an initial cut. With this arrangement, after the initial cut is made, it is obvious that the right hand wheel of the truck will drop into the low spot. If the truck were rigid, as indicated in Figure 19, it would throw 115 the belt at an incline, thus producing a ragged job.

The adjustable arrangement depicted in the diagram in Figure 20, however, overcomes this, since it permits the wheels of the truck to be regulated to insure running of the belt in a true horizontal plane for smooth surfacing operation. These diagrammatic views have been selected to emphasize the dominating importance of this 120 particular phase of the novelty.

For sake of clarity, it is to be mentioned that 103 represents a buffer roller on the carrier 92. Likewise, the work-engaging roller 90 is of a composite construction in 130

some instances including a surrounding cylindrical shell and an internal wooden core bearing as represented for example in Figure 8.

- 5 *Surfacing edges for floor work (see arrangement shown in Figure 1).*—Before attempting to surface the edges in a room, the interior of the floor is generally completely roughed off with a drum sander (not shown). Otherwise, trouble will be experienced in matching the two sanded surfaces. Now, put the same grit sanding belt 25 on the machine as was used on the drum sander for roughing off the interior of the floor.
- 10 15 Then tip the machine back so that it rests on the rear operating handle 31 and turn on the electric switch and gradually lower the machine until the sanding shoe 80 comes into contact with the unfinished edges. Slowly move it back and forth over the unfinished edges until they are sanded the same as the interior of the room.

20 The buffer 85 will have to be adjusted with respect to the small vertical toe portions of 25 the edging shoe so as to regulate the distance of approach toward the mop board. The entire shoe unit is constantly under spring pressure and co-operates nicely with the rubber spring action of the buffer in 30 case too much pressure is brought to bear against the mop board.

35 *Bench sanding (see Figure 2).*—As before intimated, the machine can be quickly and easily converted into a bench sander by removing the sanding shoe unit just described and substituting the bench sanding guide unit and raising the truck wheels at the rear of the machine so that the long roller 90 underneath the rear of the machine will 40 come into contact with the surface to be sanded. After the adjustments have been made and the sanding belt properly aligned through the adjusting device described, the machine is placed on the surface and the 45 motor set into operation and the machine moves slowly back and forth over the surface at the same time it is moved to the right and the left with the left hand on the front steering handle. This motion gives 50 a see-sawing action and tends to level off the surface, leaving it perfectly free from sanding belt marks.

55 *Changing abrasive belt.*—To change the abrasive belt, tip the machine up so that it rests on edger shoe or bench sanding pulley, whichever may be attached, and apply enough pressure on the machine to compress the belt tensioning spring until the lock pin located on the open side of the machine 60 drops in place.

The lock pin holds the belt tensioning spring in a position so that all tension is taken off of the sanding belt thus making it easier to replace the belt. The sanding belt 65 can be most conveniently replaced by laying

the machine on its side so that the open side of the machine is up.

Alignment of sanding belt.—Frequently, new belts do not track perfectly over the sanding shoe due to the belts being stiff, but after running a few moments the belts usually limber up and find their natural running position.

70 The sanding belts are one-quarter of an inch wider than both edger and bench sanding shoe, therefore, when they are in proper alignment they should project about one eighth of an inch beyond each edge of the sanding shoes. If they do not run approximately in this position, align them by slightly adjusting the running position of the belt tightening pulley which is controlled by the adjusting screw with the knurled head screw located near the front of the machine 75 on the left hand side.

80 The amount of adjusting required to align the belt is very slight, and will depend a great deal on the judgment of the operator, but after two or three adjustments have been made, it will be comparatively simple to 85 adjust the belts to the proper running position.

90 *General construction.*—The major portion 95 of this machine, which includes the frame, motor housing, handles, sanding shoe castings and units and truck wheel brackets is of aluminum alloy construction. This gives assurance that the highest quality and lightest weight material is used in rendering the sanderplane exceedingly practical from 100 every angle, but especially from that of portability, such as is essential in a manually operated electric motor operated machine.

105 It will be observed, though no novelty is claimed for it, that the motor is especially designed for ventilation and fan cooling to add to the practicability of the complete construction. Then too, the top handle 33 is detachably mounted so that it can be quickly removed, thus reducing the machine height to a minimum for working in cramped spaces. It is of importance to note 110 that a machine of this kind weighs about thirty pounds when it is complete and ready for operation, although it is light enough to be operated with ease, it still has sufficient weight to give proper proportions and balance for use either as a floor machine or a bench machine.

115 120 The gist of the combination equipment and the standardization and interchangeability of features is that the single machine fulfills the requirements of two machines. It eliminates hand planing and hand sanding whether sanding edges on the butt ends of floors, or conditioning cabinets, trims, bench and repair shop work.

125 130 Numerous commercial features and advantages accompany a machine characterized by such versatile arrangements. It is

thought unnecessary however, to delve further into these specific phases of the machine for they will be appreciated and clearly understood by persons skilled in the art to which the invention relates.

Generically comprehended, it will be observed that one feature of novelty of the organization is predicated upon a portable sanding machine such as is adapted to rest 10 on the floor or any other surface to be conditioned and treated. At the back of the frame, as well as at the front, are transverse spaced parallel guide devices. The pulleys 15 24 constitute one guide device, and the belt guiding unit at the front constitutes the other, whether it be the sanding shoe, or the especially designed sheet metal plate 58.

In the floor type, (Figure 1), there is a stationary shoe which extends forwardly 20 below and in advance of the idler pulley, wherein the bottom of the shoe adjacent the front end is substantially horizontal and the toe portion of comparatively small vertical height. The provision of an endless 25 belt trained over these various elements, together with the flexible metal platen and backing plate co-operating with the inner portion of the lower flight of the belt is a feasible and practical arrangement.

30 Additional novelty is predicated upon the adaptation of a portable motor equipped frame having the spring contained mounting stems on the forward portion to accommodate the interchangeable units, the spring 25 35 constituting tensioning means for bodily shifting the units forwardly into yieldable engagement with the front flight of the belt so as to constantly maintain the belt under elastic tension.

40 The provision of the automatically operable spring-pressed latch on the casting of the interchangeable units together with the keeper holes to allow the unit to be snapped into an inner position to aid in replacing or 45 removing the belt is important. The outer keeper hole in the stem 43 (see Figure 7) which holds the unit against displacement unless manually released, is an advantageous detail.

50 Further novelty is founded on the duplex arrangement of work engaging roller and wheeled truck at the rear of the structure permitting the selective adjustment of these individual parts so as to permit the machine 55 to be used successfully for either work on the floor or on the bench.

Many other structural as well as commercial features and advantages are comprehended in this application. Further exemplification of such points however is believed 60 to be unnecessary.

I claim:

1. In a portable sanding machine of the class described, a frame, a tubular stem carried thereby, a stud associated in spaced

parallelism with said stem, an expansion coiled spring confined in the bore of said stem, an interchangeable belt guide unit comprising a casting including a socket telescopically receiving said stem and spring, 70 and an eye slidable on said stud.

2. In a portable sanding machine of the class described, a frame, a tubular stem carried thereby, a stud associated in spaced parallelism with said stem, an expansion 75 coiled spring confined in the bore of said stem, an interchangeable belt guide unit comprising a casting including a socket telescopically receiving said stem and spring 80 and an eye slidable on said stud, said stem being formed with longitudinally spaced keeper holes, and a spring-pressed latch on said body portion automatically and selectively engageable with said holes for maintaining the unit in inner and outer positions 85 respectively.

3. In a portable sanding machine of the class described, a frame, a wheeled truck at the rear end of the frame, an adjacent belt drive pulley, a motor on the frame, an operating connection between the motor and the pulley, a tubular stem on the forward portion of the frame, a spring therein, a guide unit comprising a socketed body 90 95 slidable on said stem and co-operable with said spring, a resilient guide shoe constituting a part of said unit, and an adjustable buffer associated with said shoe.

4. In a portable sanding machine of the class described, a frame, a wheeled truck at the rear end of the frame, an adjacent work belt drive pulley, a motor on the frame, and an operating connection on the frame between the motor pulley, a stem on the forward portion of the frame, a spring carried 100 105 thereby, a guide unit comprising a socketed body slidable on said stem and co-operable with said spring, a resilient guide shoe constituting a part of said unit, an adjustable buffer associated with said shoe, a resilient platen plate on the frame, an endless belt trained over said pulley, shoe and plate, and forward and rear handles supported from the frame for aiding in steering and manipulating the machine.

5. In a portable sanding machine of the class described, a frame, a belt driving pulley mounted for rotation on the frame, a motor operatively connected with said pulley, a forwardly projecting longitudinally disposed tubular stem on the frame in advance of said pulley, a coil spring confined in the bore of said stem, a stud supported alongside of and in spaced parallelism with said stem, a belt guide unit comprising a body having a socket telescopically receiving said spring and stem, having an eye sliding on said stud, an idler pulley, an adjustable bumper, and a flexible edging shoe. 110 115 120 125

6. In a portable sanding machine of the

- class described, a frame, a belt driving pulley mounted for rotation on the frame, a motor operatively connected with said pulley, a forwardly projecting longitudinally disposed stem on the frame in advance of said pulley, a coil spring mounted on said stem, a stud supported alongside of and in spaced parallelism with said stem, a belt guide unit comprising a body having a socket telescopically receiving said spring and stem, having an eye sliding on said stud, a horizontal idler, an adjustable bumper, and a flexible edging shoe, a belt trained over the pulley, idler and shoe, and having its front flight receding rearwardly of the bumper, together with a secondary shoe in the nature of a flexible platen on the frame between the shoe and pulley and engaging the lower flight of the belt.
10. In a portable sanding machine of the class described, a frame, a belt driving pulley mounted for rotation on the frame, a motor operatively connected with said pulley, a forwardly projecting longitudinally disposed tubular stem on the frame in advance of said pulley, a coil spring confined in the bore of said stem, a stud supported alongside of and in spaced parallelism with said stem, a belt guide unit comprising a body having a socket telescopically receiving said spring and stem, having an eye sliding on said stud, a horizontal adjustable idler, an adjustable bumper, and a flexible edging shoe, a belt trained over the pulley, idler and shoe, and having its front flight receding rearwardly of the bumper, together with a secondary shoe in the nature of a flexible platen on the frame between the shoe and pulley and engaging the lower flight of the belt, a front handle on the frame, a rear handle detachably mounted on the motor, an adjustable truck on the rear portion of the frame rearwardly of the driving pulley, and floor engaging wheels carried by said truck.
15. As a new product of manufacture, an abrasive belt guide for interchangeable releasable connection with a portable sander-plane of the class described comprising a cast body having a stem and spring receiving socket, a spring pressed latch mounted on said body, a guide and retaining eye carried by the body, a bracket on said body, an arm adjustable on said bracket, a shaft projecting laterally from said arm, a block fastened to said shaft, and a belt guide carried by said block, said guide being of substantially V-shaped form with the intermediate portions of its converging walls formed with longitudinal depressions to aid in dissipation of heat.
20. In a portable sanding machine of the class described, a frame, an endless belt, means for operably mounting the belt on said frame, operating means for said first named means, and a duplex carriage on the rear portion of said frame embodying a roller carrier and an independently adjustable wheeled truck.
25. In a portable sanding machine of the class described, a frame, an endless belt, means for operably mounting the belt on said frame, operating means for said first named means, and a duplex carriage on the rear portion of said frame embodying a roller carrier and an independently adjustable wheeled truck having an attaching yoke, together with lifting spring means for said truck and adjusting and retaining screws on the carrier co-operable with companion portions of the truck yoke.
30. In testimony whereof I affix my signature.
- HARRY L. MYERS.
